UNITED STATES PATENT OFFICE.

MURRAY DENHAM LEWIS, OF SYDNEY RIVER, CANADA.

SELF-MITERING CORNICE-MOLD.

SPECIFICATION forming part of Letters Patent No. 727,647, dated May 12, 1903.

Application filed September 2, 1902. Serial No. 121,853. (No model.)

To all whom it may concern:

Be it known that I, MURRAY DENHAM LEWIS, a subject of the King of Great Britain, residing at Sydney River, county of Cape Breton, Province of Nova Scotia, Canada, have invented certain new and useful Improvements in Self-Mitering Cornice-Molds; and I do hereby declare that the following is a full, clear, and exact description of the invention, such as will enable others skilled in the art to which it appertains to make and use the same.

My invention relates to an apparatus for molding interior cornices of buildings, such as ceilings and the like, and especially designed for producing automatically miter joints or corners by the ordinary strickling process and without the necessity of any hand-molding.

My invention embraces the device herein shown and whose operation will be presently described; and it consists in the combinations and constructions hereinafter described and claimed.

In the drawings accompanying this specification, Figure 1 is a perspective view of an interior or ceiling cornice, showing my improved apparatus in the operation of molding the cornice. Fig. 2 is a plan view of the apparatus. Fig. 3 is an oblique sectional elevation taken on the line 3 3 of Fig. 2. Fig. 4 is a side elevation from the left side or a front elevation of the apparatus as shown in Fig. 1.

The same numerals of reference denote like parts in each of the figures of the drawings.

My improved apparatus consists, primarily, of a pair of slipper-bars 5 6, which are joined together at their ends in the form of a right angle and secured firmly in this position by means of a triangular gusset 7, of brass or other metal plate. From the angle 8, formed by the two meeting slipper-rods, rises a framework, comprising a pair of jaws or clamping-plates 9, which are parallel to each other and lie in a plane bisecting the right angle formed by the two slipper-rods, as shown. These are separated from each other by a strip of sheet metal 10, and the jaws 9 are secured to each other and the strip 10 by means of rivets 11. The jaw-plates are firmly and rigidly braced in their position by means of oblique handle-

rods 12 13, which are secured to opposite sides of the jaws and to opposite ends of the respective slipper-rods, as shown, and these 55 may be preferably constructed of metal tubing soldered or welded to the clamping plates or jaws 9 and secured to the slipper-rods by screws or other fastenings 14.

The framework comprising the jaws may 60 be appropriately centered and secured in place at the angle of the slipper-rods by a screw-bolt 15 passing through the angle and through an eye 16, formed in the lower end of the strip 10, and having its head mortised 65 into a washer or wear-plate 17. At the upper ends the clamping-plates are connected together by a small flat plate 20, of metal, which is intended to rest against the ceiling during the molding operation and prevent the 70 indentation or scratching of the same.

The slipper-rods are preferably protected on their lower and outer sides by metallic shoes 18, formed of rectangularly-bent sheet-metal strips and screwed or otherwise fixed 75 to the slipper-rods, as shown in Fig. 4, wherein it is seen that the lower outside edges of the slipper-rods are preferably beveled, as at 19.

The jaws or clamping-plates 9 are, as shown, 80 not rectangular in outline, but they are intended to form securing means for a molding-templet or cutting-plate 21 of any proper form having the outline of the desired cornice-molding. This molding-plate is removable 85 secured in place by short transverse bolts 22 passing through holes in the sides of the jaws and the cutting-plate. This cutting-plate may therefore be changed at will, according to the pattern desired to be molded. 90

The mode of operating my improved cornice-mold is shown in Fig. 1, and is briefly as follows: The mold is run on a wooden rod or railing-support 23, secured on the side of the wall below the cornice in the same manner as 95 ordinary cornice-molds, and the plaster forming the material of the mold is struck on with a trowel, as shown at 24, to be strickled off by the cutter 21 in its passage. In this operation it is to be observed that one of the slipper-rods 5 6 runs on the railing 23, and thus the cutter always forms an angle of forty-five degrees with the direction of motion and with the wall on the side of which it is moving. 100

The operator can commence the molding operation the same as he would an ordinary mold and run, for instance, to the left, using the right-hand handle-bar 13 to grasp the 5 mold and push it along, the slipper-rod 6 running on the railing 23. On reaching the corner of the room the opposite slipper-rod 5 will be found resting on the railing on the adjacent wall of the room, and by grasping both 10 handles temporarily the mold may now be moved along the adjacent wall away from the corner for any desired distance, and of course after the mold has passed the corner only one 15 of the handle-bars—as, for instance, in this ease the handle-bar 12—need be grasped. The molder can finish the piece started on to any distance from the corner in this manner and then turn the apparatus around its axis through ninety degrees, so as to have 20 the right-hand side next the wall, the same as in its original position in Fig. 1, and so proceed to the next corner, and so around the room. It will thus be seen that the mold enables the cornicer to finish a right-angled miter and finish fairly well any other miter, or, 25 if desired, the apparatus may be fitted to any suitable angle by joining the slipper-rod 5 and 6 at that angle. This, therefore, does away with all hand labor in finishing up the 30 cornice by hand, such as is necessary with the molds now used, because from three to six inches in the corner are left which cannot be strickled off by the mold. It will be seen, however, that the operator can take out the 35 connecting-plate and substitute as many different patterns as he wishes. For making a larger-sized cornice a larger-sized mold would of course have to be used.

While I have shown in the accompanying 40 drawings the preferred form of my invention, it will be understood that I do not limit myself to the precise form shown, for many of the details may be changed in form or position without affecting the operativeness or 45 utility of my invention, and I therefore reserve the right to make all such modifications as are included within the scope of the following claims or of mechanical equivalents to the structures set forth.

Having thus described my invention, what 50 I claim as new, and desire to secure by Letters Patent, is—

1. A cornice-mold comprising a pair of slipper-rod 55 connected together end to end at right angles with each other, a triangular gusset-plate connecting the two slipper-rod at the angle, a pair of parallel clamping-plates mounted at a short distance apart in a plane bisecting the angle between the rods, a mold- 60 ing-plate removably secured between said clamping-plates, a separating web or strip be-

tween the two clamping-plates and having a lug formed on its lower end, and a screw-bolt passing through the two slipper-rod at the angle and also through the gusset-plate and a 65 hole in said lug and securing the parts together, substantially as described.

2. A cornice-mold comprising a pair of slipper-rod connected together end to end at right angles with each other, a triangular gusset-plate connecting the two slipper-rod at the angle, a pair of parallel clamping-plates mounted at a short distance apart in a plane bisecting the angle between the rods, a molding-plate removably secured between said 75 clamping-plates, a separating web or strip between the two clamping-plates and having a lug formed on its lower end, and a pair of oblique handle-rods joining the upper portion of the clamping-plates at opposite sides thereof to the free ends of the respective slipper- 80 rods.

3. A cornice-mold comprising a pair of slipper-rod connected together end to end and at right angles with each other, a triangular gusset-plate connecting the two slipper-rod at the angle, a pair of parallel clamping-plates mounted at a short distance apart in a plane bisecting the angle between the rods, a molding-plate removably secured between said 90 clamping-plates, a separating web or strip between the two clamping-plates and having a lug formed on its lower end, and a set of metallic shoes covering the outside and lower edges of said slipper-rod.

4. A cornice-mold comprising a pair of slipper-rod connected together end to end at right angles with each other, a triangular gusset-plate connecting the two slipper-rod at the angle, a pair of parallel clamping-plates mounted at a short distance apart in a plane bisecting the angle between the rods, a molding-plate removably secured between said 100 clamping-plates, a separating web or strip between the two clamping-plates and having a lug formed on its lower end, a screw-bolt passing through the two slipper-rod at the angle and also through the gusset-plate and a hole in said lug and securing the parts together, a pair of oblique handle-rods joining the upper portion of said clamping-plates to the free 105 ends of the respective slipper-rod, and a horizontal ceiling-rest 20 covering the upper ends of said clamping-plates, substantially as described.

In witness whereof I have hereunto set my hand in the presence of two witnesses.

MURRAY DENHAM LEWIS.
